UNITED STATES PATENT OFFICE

ROBERT G. CLARK, OF BROOKLYN, NEW YORK

DESIGN-WEAVING ATTACHMENT FOR LOOMS

Application filed March 19, 1928. Serial No. 262,719.

My invention relates to devices for design weaving and has for its main objects to provide a device by means of which design weaving may be done at a greatly increased 5 rate of speed and with a minimum expenditure of time and labor in setting up or making ready the loom.

Another object is to provide a device on which inexpensive patterns, enlarged duplicates 10 of the designs to be woven and thus easy to make, may be used for transferring the designs to the fabric, and on which the design weaving may be started and stopped, while the loom is in operation, so as to inter- 15 weave plain fabric. A further object is to provide a device of simple and inexpensive construction, automatic in operation and requiring but slight skill and attention on the part of the operator.

20 These and various other objects and advantages will be clearly understood from the following description and from the accompanying drawings of preferred embodiments, but it will be readily seen that cer- 25 tain modifications might be made without departing from the scope of the invention.

In the drawings,

Fig. 1 is a front elevation of a circular loom, drawn partly in cross-section and 30 showing the design-weaving attachment attached thereto,

Fig. 2 is a fragmentary, cross-sectional elevation showing parts of both the loom and the attachment,

35 Fig. 3 is a side elevation of a modification of the attachment shown with parts of the loom in cross-section,

Fig. 4 is a front elevation of Fig. 3,

40 Figs. 5 and 6 are fragments of certain parts of the loom,

Figs. 7 and 8 are diagrams illustrating the arrangement of the pattern on the design rollers, and

45 Figs. 9 and 10 are diagrams of a certain cam and cam rollers.

The loom on which the design-weaving attachment is employed will first be described in a general way. This loom is shown and described in detail in my co- 50 pending application Serial No. 262,161. It

is distinctly understood, however, that this particular loom has been illustrated only to facilitate the description of the attachment and that it is not the intention to limit the use of the invention to such looms, but that I intend to employ it on any type of looms on which it may be used to advantage.

The loom illustrated is a circular loom having a plurality of warp thread bobbins 10 attached close to the periphery of a circular table 11. The warp threads 12 are engaged by the heddles 13 and 13^a which lift and lower alternate threads so that the revolving shuttles 14, which carry the weft thread bobbins 15, may pass between these threads. The heddles are actuated by the cams 16 and 17 which are annular and extend around the periphery of the disc wheel 18 which rotates on the stationary shaft 19. These cams have wavy cam faces which cause the up and down movements of the heddles and they are separated by a spacer 20.

The shuttles 14, which are revolved by pinions 21 to which motion is imparted by the spiral crown gear 22 rotatably mounted on the stationary shaft 19, are provided with aprons 23 and ribs 24, 25, 26, 27 and 28 which further separate the warp threads as they pass between them. The weft threads 29, which are laid between the warp threads by the shuttles, are pressed into place by the cam-actuated fingers 30 which also feed the woven fabric 31 up through a circular throat 32. The fabric, which when finished is tubular, is wound on the roller 33. The table 11, the frame 34 and the shaft 35 are all supported by a plurality of upright posts 36. This will suffice for the description of the loom; the design-weaving attachment will now be explained in detail.

Referring first to Figs. 1 and 2, a frame 37 is supported on the posts 36 some distance below the table 11. To this frame is secured a plurality of bearings 38 on which the frames 39 are hinged. The pattern drums 40, of which four are shown in Fig. 1, rotate in bearings 41 formed on top of the frames 39. Each frame is provided with a cross bar 42 on top of which a cam roller

100

43 is mounted. All of these cam rollers are engaged against a cam ring 44, secured on a disc 45 which is rotatably mounted on the stationary shaft 19. The cam rollers are held in engagement with the cam ring by tension springs 46, secured as shown. The disc 45 is provided with an operating handle 47 and the face of the cam ring 44 is so designed that a slight rotating movement will force the cam rollers outward and thus the drums 40. In some cases the cam ring is so constructed that the movement of the handle 47 in one direction will disengage certain drums and a movement in the opposite direction will disengage certain other drums. The operation of these cams and cam rollers will be readily understood by referring to Figs. 9 and 10. In Fig. 9 it will be seen that a movement of the cam ring 44 in either direction will force the cam rollers 43 outward. In Fig. 10 it will be seen that, as cam faces are only provided between every other cam roller, a movement of the cam ring in one direction will force half of the rollers outward, and a movement in the opposite direction will force the balance of the rollers outward. The cam faces are indicated by the numerals 44^a and 44^b. As the cam rings are interchangeable various other arrangements of cam faces may be employed.

The pattern drums are each provided with a ratchet wheel 48. These ratchet wheels have been omitted on the three drums shown on the right-hand side of Fig. 1, but one is plainly shown on the drum on the left-hand side. The ratchet wheels are rotated by pawls 49 which are attached to rocker arms 50, pivoted in bearings 51 which are cast integral with the circular casting 52. A cam-engaging rod 53 is attached to the other end of the rocker arm and is guided in a hole drilled in the casting 52.

The rods 53 all engage on the annular cam 55, the face of which is wavy so as to impart a rocking motion to the arms 50 as the disc wheel 18, on which it is attached, rotates. The motion of the rocker arms causes the pawls 49 to rotate the ratchet wheels and consequently the drums. Tension springs 56 hold the rods 53 in engagement with the cam 55, while pawls 57 prevent the drums from overrotating. The pawls 57 are adjustable by means of screws 58 and are held in engagement by tension springs 59.

The heddles 13 and 13^a, which are bifurcated at their upper ends to accommodate the warp threads as shown in Fig. 5, are guided by two annular, slotted, spacers 60 and 61, one of which is attached to the table 11 and one to the casting 52^a. The lower ends of the heddles are formed with narrowed portions 62 and 62^a which engage, respectively, on the cams 16 and 17. As already stated, the faces of these cams are

wavy and impart an up and down movement to the heddles, in such a manner, that all the heddles are alternately up or down, prior to the passing of the shuttles.

A latch 63 prevents the heddles from falling off the cams when in the bottom of a wave, as would otherwise be the case. This latch, of which there is one for each heddle, normally engages in a notch 64 which is formed in the heddle. When so engaged displacement of the heddle from the cam is impossible. Above the notch 64, a clearance space 65 is provided and if the latch is lifted so as to enter this clearance space, as shown by the dotted lines 66, the heddle will be displaced from the cam face, as shown by the dotted position 67. The latches, which normally lift and fall with the heddles, are provided with a feeler 68 at their lower ends and they are rockingly suspended in a slotted, annular spacer 69 which is secured to the casting 52.

If a raised pattern 70, such for example as shown on one of the drums in Fig. 1, is placed on one or more of the drums, the feeler 68, as it is lifted from the face of the drum by the pattern, releases the latch 63 from the notch 64 and causes the heddle to drop from the cam face. This causes the warp thread in the particular heddle or heddles so displaced to be lowered so that the shuttle may pass over such thread or threads. This transfers the design to the woven fabric as shown at 71. The heddles are restored to the cam faces by guides 72 which are riveted on the outer side of the cam 16. As the drums are further removed from the center of the loom than the woven fabric, the patterns can be made several times larger than the design woven. This is plainly shown in Fig. 1.

It is evident that any design may thus be transferred from the pattern drums to the fabric. If it is desired to weave a design of greater length than can be accommodated on the drum itself, an endless belt 73 is employed. This arrangement is shown in Fig. 1. The belt, to which the pattern is attached, passes over the drum 40, over an idler 74 supported on an arm 75, and over a pulley 76 which is supported on a swinging arm 77. It will be seen that by operating the handle 47, the weaving of the design may be stopped at any time and that, while so stopped, the loom will weave plain fabric. Fig. 6 shows the thread spacing ring 78 which is placed below the points of the needles and provided with easily threaded notches 79.

The drums so far described, when supplied with patterns, will transfer a plurality of designs lengthwise of the tubular fabric woven. When it is desired to transfer a continuous design around the fabric the modification shown in Figs. 3, 4, 7 and 8 is

employed. This modification will now be explained.

The loom is the same as previously described and the heddles are actuated as before. The pattern drums 80, which in this case are rather narrow, are mounted on bearings 81 which in turn are slidably mounted on brackets 82 secured to the frame 37 of the loom. The ratchet 83 is placed on the drum shaft 84 and correctly aligned with the drum by means of the pin 85.

The heddles are provided with notches 86 in which the latches 87 engage and with clearance spaces 88, but in this case the feelers 89 are separate pieces and engage with arms 90 which are formed on the latches. The latches rock in slots cut in the spacing ring 91 and the feelers are offset, as shown in Fig. 4, so as to engage with the narrow pattern drums. The drums are rotated by the pawls 92 which are attached to a rocker arm 93 which in turn is pivoted on the bracket 94. The other end of the rocker arm is actuated by a ring cam 95 which has a wavy groove 96. Drums of various sizes may be used by sliding the bracket 81 in the slot 97.

Fig. 7 shows how the drums are aligned by placing them on a center shaft 98 and an aligning pin 99, while the patterns 100 are attached. Fig. 8 shows how the drums are spaced around the circular loom, the offsetting of the feelers making this possible.

Having thus described my invention, what I claim as new and wish to protect by Letters Patent is:

1. In combination with a circular loom having independent cam-operated reciprocating heddles each of which engages a warp thread; one or more drums; patterns attached on said drum or drums; a plurality of drum-engaging feelers actuated by said patterns; means associated with said feelers and said heddles for preventing reciprocation of one or more of said heddles, by displacing it or them from its or their respective cam, while the feelers are actuated by the patterns; and means for rotating said drum in timed relation to the loom.

2. In combination with a circular loom having independent cam-operated reciprocating heddles each of which engages a warp thread; a plurality of drums; patterns attached on said drums; a plurality of drum-engaging feelers, equal to the number of warp threads employed on the loom, actuated by said patterns; means associated with said feelers and said heddles for preventing reciprocation of one or more of said heddles, by displacing it or them from its or their respective cam, while the feelers are actuated by the patterns; means for rotating said drums in timed relation to the loom; and means for disengaging one or more of the drums at a time from said feelers.

3. In combination with a circular loom having independent cam-operated reciprocating heddles each of which engages a warp thread; a plurality of drums; patterns attached on said drums; a plurality of drum-engaging feelers, equal to the number of warp threads employed on the loom, actuated by said patterns; means associated with said feelers and said heddles for preventing reciprocation of one or more of said heddles, by displacing it or them from its or their respective cam, while the feelers are actuated by the patterns; means for rotating said drums in timed relation to the loom; and means for disengaging all the drums from all of said feelers simultaneously.

4. In combination with a circular loom having independent cam-operated reciprocating heddles each of which engages a warp thread; a plurality of narrow drums; patterns attached to said drums; a plurality of drum-engaging feelers, equal to the number of warp threads employed on the loom, actuated by said patterns; said feelers having their drum-engaging ends offset so that a plurality of feelers may work on each drum; means connected with said feelers and said heddles for preventing reciprocation of one or more of the heddles, by displacing it or them from its or their respective cam, while the feelers are actuated by the patterns; and means for rotating said drums in timed relation to the loom.

5. In combination with a circular loom having independent cam-operated reciprocating heddles each of which engages a warp thread; a plurality of narrow drums; patterns attached to said drums; a plurality of drum-engaging feelers, equal to the number of warp threads employed on the loom, actuated by said patterns; said feelers having their drum-engaging ends offset so that a plurality of feelers may engage on each drum; means connected with said feelers and said heddles for preventing reciprocation of one or more of the heddles by displacing it or them from its or their respective cam, while the feelers are actuated by the patterns; means for rotating said drums in timed relation to the loom; and means for aligning all of said drums while the patterns are being attached and for attaching them in correct relation to each other on the loom.

6. In combination with a circular loom having independent cam-operated reciprocating heddles each of which engages a warp thread; a plurality of narrow drums; patterns attached on said drums; a plurality of drum-engaging feelers, equal to the number of warp threads employed on the loom, actuated by said patterns; said feelers having their drum-engaging ends offset so that a plurality of feelers may engage on each drum; means connected with said feelers

and said heddles for preventing reciprocation of one or more of the heddles, by displacing it or them from its or their respective cam, while the feelers are actuated by the patterns; means for rotating said drums in timed relation to the loom; and said drums attached to slidably mounted brackets so that various sizes of drums may be employed.

10. 7. In combination with a circular loom having independent cam-operated reciprocating heddles each of which engages a warp thread; one or more narrow drums; patterns attached to said drums; a plurality of drum-engaging feelers actuated by said patterns; said feelers having their drum-engaging ends offset so that a plurality of fingers may work on each drum; means connected with said feelers and said heddles for preventing reciprocation of one or more of the heddles by displacing it or them from its or their respective cam, while the feelers are actuated by the patterns; and means for rotating said drums in timed relation to the loom.

15. 8. In combination with a circular loom having independent cam-operated reciprocating heddles each of which engages a warp thread; a plurality of drums; patterns attached to said drums; a plurality of drum-engaging feelers, equal to the number of warp threads employed on the loom so that no rethreading is necessary when the patterns are changed, actuated by said patterns; 20 means associated with said feelers and said heddles for preventing reciprocating of one or more of said heddles, by displacing it or them from its or their respective cam, while the feelers are actuated by the patterns; 25 and means for rotating said drums in timed relation to the loom.

9. In combination with a circular loom having independent cam-operated reciprocating heddles each of which engages a warp thread; a plurality of drums; patterns attached to said drums; a plurality of drum-engaging feelers, equal to the number of warp threads employed on the loom so that a continuous design may be woven transversely of the fabric, actuated by said patterns; means associated with said feelers and said heddles for preventing reciprocation of one or more of said heddles, by displacing it or them from its or their respective cam, 45 while the feelers are actuated by the patterns; and means for rotating said drums in timed relation to the loom.

10. 10. In combination with a circular loom having independent cam-operated reciprocal heddles each of which engages a warp thread; one or more drums; patterns attached on said drum or drums, said patterns being larger than the designs reproduced from them; a plurality of drum-engaging feelers actuated by said patterns;

means associated with said feelers and said heddles for preventing reciprocation of one or more of said heddles, by displacing it or them from its or their respective cam, while the feelers are actuated by the pattern; and means for rotating said drum or drums in timed relation to the loom.
